[57] CLAIM

The ornamental design for a cover boot for cables, as shown and described.

DESCRIPTION

FIG. 1 is a perspective view of my invention for a cover boot for cables;

FIG. 2 is a front elevational view of the invention;

FIG. 3 is a side elevational view of the invention, the opposite side is a mirror image thereof;

FIG. 4 is a rear elevational view of the invention;

FIG. 5 is a top plan view of the invention;

FIG. 6 is a bottom plan view of the invention;

FIG. 7 is a perspective view of an alternative embodiment of my invention for a cover boot for cables;

FIG. 8 is a front elevational view of the alternative embodiment;

FIG. 9 is a side elevational view of the alternative embodiment, the opposite side is a mirror image thereof;

FIG. 10 is a rear elevational view of the alternative embodiment;

FIG. 11 is a top plan view of the alternative embodiment; and

FIG. 12 is a bottom plan view of the alternate embodiment.
